US0D1093139S

(12) **United States Design Patent** (10) **Patent No.:** **US D1,093,139 S**
(45) **Date of Patent:** **** Sep. 16, 2025**

(54) **PACKAGING**

(71) Applicant: **GPI Systems AB**, Lund (SE)

CH 145349-0003 6/2020
CH 145349-0004 6/2020

(72) Inventor: **Fredrik Konstenius**, Lund (SE)

(Continued)

(73) Assignee: **GPI Systems AB**, Lund (SE)

(**) Term: **15 Years**

(21) Appl. No.: **29/837,677**

(22) Filed: **May 7, 2022**

Related U.S. Application Data

(62) Division of application No. 29/737,222, filed on Jun. 7, 2020, now Pat. No. Des. 966,099.

(30) **Foreign Application Priority Data**

(57) **CLAIM**

The ornamental design for packaging, as shown and described.

DESCRIPTION

FIG. 1 is a front, left side, top perspective view of packaging showing my new design;

FIG. 2 is a rear, right side, bottom perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The vertical broken lines along the right side of the packaging in the drawings illustrate portions of the packaging that form no part of the claimed design.

1 Claim, 4 Drawing Sheets
